US00D774815S

(12) **United States Design Patent** (10) Patent No.: **US D774,815 S**
(45) Date of Patent: **** Dec. 27, 2016**

(54) **SHADE COVER**

(71) Applicant: **BRAVO SPORTS**, Santa Fe Springs, CA (US)

(72) Inventors: **Jack B. Lovley, II**, Lake Forest, CA (US); **Joseph C. Klingl**, Los Angeles, CA (US)

(73) Assignee: **Bravo Sports**, Sante Fe Springs, CA (US)

(**) Term: **15 Years**

(21) Appl. No.: **29/537,208**

(22) Filed: **Aug. 24, 2015**

Related U.S. Application Data

(63) Continuation of application No. 29/484,192, filed on Mar. 6, 2014, now Pat. No. Des. 737,066.

U.S. Appl. No. 60/467,698, May 1, 2003, Churchill.

Primary Examiner — Ricky Pham

(74) Attorney, Agent, or Firm — Knobbe Martens Olson & Bear, LLP

CLAIM

The ornamental design for a shade cover, as shown and described.

DESCRIPTION

FIG. 1 is a bottom-oriented perspective view showing a bottom surface of a shade cover.

FIG. 2 is a top-oriented perspective view showing a top surface of a shade cover of FIG. 1.

FIG. 3 is a front view of the shade cover of FIG. 1.

FIG. 4 is a rear view of the shade cover of FIG. 1.

FIG. 5 is a left side view of the shade cover of FIG. 1.

FIG. 6 is a right side view of the shade cover of FIG. 1.

FIG. 7 is a top view of the shade cover of FIG. 1; and,

FIG. 8 is a bottom view of the shade cover of FIG. 1.

Where utilized, the broken lines show portions of the shade cover that form no part of the claimed design.

1 Claim, 8 Drawing Sheets

UNITED STATES PATENT AND TRADEMARK OFFICE
CERTIFICATE OF CORRECTION

PATENT NO. : D774,815 S
APPLICATION NO. : 29/537208
DATED : December 27, 2016
INVENTOR(S) : Jack B. Lovley, II

Page 1 of 1

It is certified that error appears in the above-identified patent and that said Letters Patent is hereby corrected as shown below:

On the Title Page

Page 1 (item (73), Assignee) at Line 1, Change "Sante" to --Santa--.

Signed and Sealed this
Thirtieth Day of May, 2017

Michelle K. Lee
Director of the United States Patent and Trademark Office
